United States Patent Office.

GEORGE JONES, OF NEW HAVEN, CONNECTICUT.

Design No. 3,076, dated June 30, 1868.

DESIGN FOR A COFFEE-URN.

The Schedule referred to in these Letters Patent and making part of the same.

TO ALL WHOM IT MAY CONCERN:

Be it known that I, GEORGE JONES, of New Haven, in the county of New Haven, and State of Connecticut, have invented a new Design for a Coffee-Urn; and I do hereby declare the following, when taken in connection with the accompanying drawing, to be a full, clear, and exact description of the same, and which said drawing constitutes part of this specification, and represents a front view.

This invention relates to a design for a tea or coffee-urn, and consists of a base, supported by legs, in imitation of animals, the claws of which rest upon a ball. Above the base is a plain cylinder, with a Grecian key-moulding at the base and neck, a lion's head to receive the spout, and a dog's head upon opposite sides, as handles, the whole surmounted by a cover, upon which a bird rests, as a handle for the cover, all as fully shown in the accompanying illustration.

What I claim as my invention, and desire to secure by Letters Patent, is—

The design for a tea or coffee-urn, as herein fully illustrated and described.

GEO. JONES.
